UNITED STATES PATENT OFFICE.

PETER T. COFFIELD, OF DAYTON, OHIO, ASSIGNOR TO THE COFFIELD MOTOR WASHER COMPANY, OF DAYTON, OHIO, A CORPORATION OF OHIO.

WATER-MOTOR.

1,205,857.

Specification of Letters Patent.

Patented Nov. 21, 1916.

Application filed May 10, 1915. Serial No. 26,951.

To all whom it may concern:

Be it known that I, PETER T. COFFIELD, a citizen of the United States, residing at Dayton, in the county of Montgomery and State of Ohio, have invented certain new and useful Improvements in Water-Motors; and I do declare the following to be a full, clear, and exact description of the invention, such as will enable others skilled in the art to 5 which it appertains to make and use the same, reference being had to the accompanying drawings, and to the letters and figures of reference marked thereon, which form a part of this specification.

10 This invention relates to new and useful improvements in water motors of the type especially designed for operating domestic washing machines.

15 The improvements are specific in their character and relate to a further perfection 20 of the motor shown and described in Letters Patent No. 1,082,477, granted to Isador Yassenoff on December 23, 1913, and assigned to The Coffield Motor Washer Company of 25 Dayton, Ohio, of which I am the president.

20 The objects and purposes of the improvements are to increase the efficiency of the motor in inexperienced hands. This is accomplished by certain specific improvements 30 for compressing the spring up to the requisite point only and thus relieving it of any over-compression, and specific means for sealing the attached end of the motor cylinder without employing packing which is usually 35 undesirable in a motor of this character.

40 In the accompanying drawings, Figure 1 is a longitudinal sectional elevation of the motor containing my improvements on the line 1—1 of Fig. 4; Fig. 2 is a longitudinal elevation taken on the line 2—2 of Fig. 4; Fig. 3 is a cross-sectional view on the line 45 3—3 of Fig. 1; and Fig. 4 is a cross-sectional view on the line 4—4 of Fig. 1.

45 In the description to follow and in the drawings, similar reference characters indicate corresponding parts.

50 1 designates the cylinder or motor casing containing a reciprocable piston 2 attached to a hollow rod 3 extending out of an end 55 of the cylinder through an apertured boss 4 and gland 5 fitting therein. The end of the rod so extended out of the motor cylinder is designed to be attached to any suitable power transmission device such as a rack and pinion which elements are not shown.

The end of the cylinder opposite that through which the rod 3 projects, is provided with a separate inserted head 6 which provides inlet and exhaust chambers 7 and 8, respectively, for the motive fluid to enter 60 and pass out of the motor. A cap 10 is attached to the end of the cylinder and engages the outer side of the chambered head 6 and holds the same snugly in position against the annular shoulder 9 formed in the end of the cylinder. This cap 10 has a screw-threaded engagement with the extreme end of the cylinder and provides a chamber 11 which communicates with the opposite end of the cylinder through a channel 12 which is formed in the wall of the cylinder. The inlet and exhaust chambers or passages 7 and 8 in the inserted head 6 register with passages provided in oppositely disposed nozzles 13 which project from 65 the end of the cylinder and to which the usual inlet and outlet hose (not shown) are attached by the provision of the inserted head 6 and the screw-cap 10 screwed into the end of the cylinder against said inserted 70 head, a very efficient joint is obtained to prevent leakage of the motor without the employment of packing which is objectionable in motors of this character which are solely confined to domestic use. A double puppet 75 inlet valve 14 and a double puppet exhaust valve 15 seat upon opposite seats in the head 6 and control the passage of the water from and to opposite sides of the cylinder. These valves, on one side of the head 6, communicate directly with the interior of the cylinder and on one side of the piston, and with the cylinder on the other side of the piston through the chamber 11 and channel 12. During the movement of the valves, the motive fluid is alternately admitted to one or the other side of the piston 2 arranged in the cylinder and the said motive fluid is likewise alternately discharged from one or the other side of said piston after it has expended its 80 force in driving the piston to the limit of its travel in one or the other direction. For example, when the valves are in the position shown in Fig. 2, the live fluid is passing through chamber 7 past the inlet valve 14 and into the chamber 11, thence through the channel 12 into the right hand side of the cylinder where it expends its force to move the piston in the direction of the arrow. Meanwhile, the motive fluid is exhausting 85 90

100 105 110

from the opposite side of the piston through the exhaust valve and chamber 8. When the piston reaches the end of its stroke, the valves 14 and 15 are shifted from the position shown in Fig. 2 and will thus permit the live fluid to pass directly into the cylinder on the opposite side of the piston and out through the channel 12 and chamber 11 to the chamber 8 in the head 6. The valves are provided with stems 16 and 17 which are connected by a yoke 18 having an apertured boss 19. The connection between the yoke 18 and the stems of the valve is effected through means of slots 20 and 21 which lie at right-angles to each other in the ends of the yoke. In connecting the yoke to said valve stems, it will be readily seen that one of the stems serves as a pivot for the movement of the yoke in connecting it with the other stem. This means of connecting the two valves is simple and efficient. When the yoke is thus connected to said valves, it is maintained in such connection by means of a stud 22 which is secured to the head 6.

A rod 23 is coupled to the yoke 18 by means of a head 24 on an end of said rod which lies within the apertured boss 19 of the yoke and thus a loose connection is made between said rod 23 and the yoke. The said rod telescopes in the hollow piston rod 3 and in entering said rod it extends loosely through an aperture in a buffer 25. Between the buffer 25 and the piston 2, a conical spring 26 is arranged around the rod 23. The end of the rod 23 which lies within the hollow rod 3 is provided with a head 27 and against the inner end of said rod 3 an apertured buffer or head 28 is placed through which the rod 23 also passes and with which the head 27 is adapted to engage when the piston is moving in one direction, for example, to the right, as seen in Fig. 2. This apertured head 28 supports the small end of the conical spring 26 and the said spring is compressed and expands between the piston and the buffer 25 or more correctly speaking between the two buffers 25 and 28. The buffer 25 being in the position shown will engage the boss 19 of the yoke as the piston is moved in one direction. The spring 26 will be compressed until the hub of the buffer 25 engages the buffer 28 and thus form a rigid contact and will cause the valves to initially unseat at which instant the spring expanding will complete the throw of said valves. In the other direction of the piston, the head 27 of the rod 23 will move the apertured head or buffer 28 to compress the spring and engage the hub of the buffer 25 and will form a rigid abutment which will cause the valves to unseat and to be completely moved by the expansion of the spring as before. Thus the valves are reversed during the reciprocation of the piston to admit and discharge the motive fluid to and from opposite sides of the piston. The abutment or head 28 coöoperating with the rod head 27 and the buffer 25 is instrumental in initially unseating the valves in one direction of movement of the piston and the abutment or head 28, buffer 25 and boss 19 accomplish the operation of the valves in the other direction. It will be understood that the spring 26 is compressed until the head 28 engages the buffer 25 in one movement, and that the said spring is compressed until said head 28 through the engagement with head 27 engages the buffer 25 in the other movement of the piston. Thus the spring is only sufficiently compressed at all times to store sufficient energy to impart a complete movement to the valves after the rigid contact has unseated them against the heavier pressures of the water holding them to their seats. Apertured projections 29 extend from the piston and afford means for loosely mounting the buffer 25 which is maintained in position thereon by pins 30. The piston is provided with packing 31 of a suitable character which is turned parallel with the circumference of the piston and engages the interior of the cylinder. A series of teeth or serrations 32 are provided under the surrounding edges of the packing on the piston to hold the packing against the sides of the cylinder and to thus permit the water to gain access to the leathers to properly saturate and expand the same after the motor has been put to use after being left idle for any length of time and the packing permitted to dry out. It will be understood that the apertured head 28 and the buffer 25 come together when the spring 26 is compressed to form the rigid abutment, as before referred to, and at the same time these elements act as bumpers to prevent over-compression of the spring and serve to preserve the efficiency of the spring and the life of the motor.

Having described my improvements, I claim.

1. In a water motor, a cylinder having a detachable chambered head at one end, double puppet inlet and exhaust valves mounted in said head, a yoke connecting said valves, a piston movable in said cylinder, a hollow rod extending from said piston on one side, a buffer engaging one side of the piston, a second buffer loosely supported on the piston, a conical spring mounted between said buffers, a rod movable in the hollow rod extending from the piston and projecting through the axes of the buffers and the spring and connected at one end to said valve yoke, said rod being adapted to engage one of the buffers to cause a compression of the spring in the movement of the piston in one direction, the other buffer being adapted to engage the valve yoke to compress the spring in the movement of the piston.

ton in the other direction, said buffers being adapted to engage each other after the spring is compressed and to thereby form a rigid abutment to unseat the valves in the movement of the piston in both directions.

2. In a water motor, a cylinder provided with an enlarged end with an interior annular shoulder therein and inlet and outlet pipes extending therefrom, a head inserted in the enlarged end of said cylinder against said annular shoulder and having inlet and outlet passages communicating with said inlet and outlet pipes, a cap inserted in the enlarged end of said cylinder and maintaining said head in rigid engagement with

said annular shoulder, to effect a watertight joint between said head and the cylinder, said cap providing a chamber on the outside of said head with which the inlet and outlet passages in said head communicate, 20 means providing a communication between said chamber and the remote end of the cylinder, valves in said head controlling the passages between the said head and the chamber on the outside thereof, a piston 25 movable in said cylinder, and means interposed between said piston and said valves for operating said valves.

In testimony whereof I affix my signature.

PETER T. COFFIELD.
